DESIGN FOR AN ALPHABET FOR FORMING MONOGRAMS FOR WEARING APPAREL OR SIMILAR ARTICLE

Charles Emmey, New York, N. Y.

Application July 7, 1938, Serial No. 78,321

Term of patent 14 years

To all whom it may concern:

Be it known that I, Charles Emmey, a citizen of the United States, residing in the city of New York and county of New York, State of New York, have invented a new, original, and ornamental Design for an Alphabet for Forming Monograms for Wearing Apparel or Similar Article, of which the following is a specification, reference being had to the accompanying drawing, forming part thereof.

The figure of the drawing is a face view of the alphabet for forming monograms for wearing ap-

parel, the letters being of no appreciable thickness.

The letters of the alphabet are characterized by the long arms being substantially inwardly curved toward the center, the top portion of the closed letters being upwardly curved.

I claim:

The ornamental design for an alphabet for forming monograms for wearing apparel or similar article, substantially as shown and described.

CHARLES EMMEY.
